US00D801361S

(12) **United States Design Patent** (10) **Patent No.:** **US D801,361 S**
Gu et al. (45) **Date of Patent:** **** Oct. 31, 2017**

(54) **DISPLAY SCREEN WITH GRAPHICAL USER INTERFACE**

(71) Applicant: **MivaLife Mobile Technology, Inc.**, Fremont, CA (US)

(72) Inventors: **Keqin Gu**, Fremont, CA (US); **Yan Qi**, Fremont, CA (US); **Tsungyen Chen**, Palo Alto, CA (US)

(73) Assignee: **MIVALIFE MOBILE TECHNOLOGY, INC.**, Grand Cayman (KY)

(**) Term: **15 Years**

(21) Appl. No.: **29/559,463**

(22) Filed: **Mar. 28, 2016**

Related U.S. Application Data

(63) Continuation of application No. 13/837,235, filed on Mar. 15, 2013, now abandoned.

(57) **CLAIM**

The ornamental design for an display screen with graphical user interface, as shown and described.

DESCRIPTION

FIG. 1 is a front view of an display screen with graphical user interface according to a first embodiment of the invention.

FIG. 2 is a front view of an display screen with graphical user interface according to a second embodiment of the invention; and,

FIG. 3 is a front view of an display screen with graphical user interface according to a third embodiment of the invention.

The broken lines showing the display screen and the remainder of the graphical user interface form no part of the claimed design.

1 Claim, 3 Drawing Sheets
